KNITTING MACHINE

Harold E. Houseman, Laconia, N. H., assignor to
Standard-Trump Bros. Machine Company,
Laconia, N. H., a corporation of Delaware

Application November 13, 1933, Serial No. 697,728

9 Claims. (Cl. 66—135)

This invention relates to a knitting machine and specifically a machine in which patterns are produced by wrapping of needles by yarn carrying fingers which may be shogged relatively to the needles. The invention is particularly adapted to rotary needle machines which are of the most satisfactory type for operation but involve difficulties in the production of shogging of the wrap fingers.

10 It is the primary object of the invention to provide a shogging control which is adapted for the production of intricate patterns. Shogging in the past has been controlled from continuously ratcheted pattern drums or, alternatively and better, by suitable set-ups of pattern chains. The use of a pattern drum for the production of shogging is very poorly adapted to rotary cylinder machines and, in any event, in either rotary or stationary cylinder machines, only very simple 15 shogging sequences may be obtained. When pattern chains are used, there is no theoretical limit to the character of the shogging sequence provided the chain is made sufficiently long. In the case of fine gauge hosiery, however, in which it may be desired to have a shogged pattern of non repetitive type extending through a very substantial portion of the leg and instep, the necessary pattern chain would have such length that it would not only be very difficult to set up, 20 but could not be conveniently handled.

In accordance with the present invention, a novel controlling arrangement is provided which is very compact and readily set up for the production of highly elaborate patterns. This shogging controlling device may be associated with means for selecting needles for wrapping. In the preferred embodiment of the invention, extremely elaborate patterns may be produced.

25 The present invention also makes possible setting up of the shogging controlling mechanism for the production of a new stocking after one has been finished; that is, if the wrap fingers are displaced from their original positions by shogging, then at the end of a wrapping operation and during the knitting of the portions of the stocking where no wrapping is desired, the wrap fingers may be brought back to their initial positions.

30 The various features of the invention particularly relating to details of construction, will be apparent from the following description read in conjunction with the accompanying drawings, in which:

Fig. 1 is a side elevation of a knitting machine with various parts omitted and broken away to

show more clearly the elements forming the subject matter of the present invention;

Fig. 2 is a horizontal section of a similar nature;

Fig. 3 is a vertical section showing certain 5 shogging controlling elements, the section being taken on the plane indicated at 3—3 in Fig. 2;

Fig. 4 is a vertical section taken as indicated at 4—4 in Fig. 3;

Fig. 5 is a horizontal section showing certain 10 details of the shogging controlling elements;

Fig. 6 is a vertical section showing a needle cylinder and cooperating elements;

Fig. 7 is a fragmentary view partly in elevation and partly in section showing wrap finger 15 controlling elements;

Fig. 8 is a fragmentary elevation showing certain controlling means connecting the shogging control and needle selecting mechanisms;

Fig. 9 is a fragmentary elevation showing 20 ratchet mechanism for effecting shogging;

Figs. 10, 11 and 12 are fragmentary views showing in plan various elements of Fig. 9;

Fig. 13 is a horizontal section showing the driving arrangement for the wrap finger carrying 25 head;

Fig. 14 is a developed interior view of the cams operating upon needles and their associated jacks and the wrap fingers; and

Figs. 15A and 15B indicate diagrammatically a 30 a type of pattern producible by the use of the present machine.

The machine which is specifically disclosed is of the rotary needle cylinder type provided with wrap fingers which are associated with individual 35 needles to carry wrap yarns about the same for the production of individual needle wrapping. The machine is of the type illustrated and described in the application of Stanley R. Shelmire, Ser. No. 623,057, filed July 18, 1932, to which reference may be made for a more complete description of certain elements which are not essentially connected with the present invention. The shogging mechanism is in a general way similar to that illustrated in my prior application Ser. No. 45 668,924, filed May 2, 1933.

Briefly stated, in its preferred form the machine is designed to produce a double sole in a stocking by the addition of a yarn in the sole of the foot portion, wrapping of the leg and instep 50 being carried out during rotary knitting. The wrapped designs are rendered more elaborate by the inclusion of shogging which serves to carry each wrap finger into cooperation with a series of adjacent needles. The machine as illustrated 55

comprises an elongated needle cylinder 2 which carries needles 4 arranged in the usual fashion and provided with different length butts so that proper selection can be made for the usual variations in knitting common to the formation of the parts of stockings. The special elongation of the needle cylinder is provided for the accommodation of jacks 5 and 7, the former of which engage the lower ends of the needles and are provided with suitable butts, and the latter of which have the formation indicated in Fig. 6, so as to be rocked about a pivotal point intermediate their ends located above series of butts illustrated in Fig. 6. The functions of these jacks will be pointed out hereafter.

At its lower end the cylinder is provided with a ring gear 6 which is driven through an intermediate gearing by the usual driving gear 8 carried by the shaft 10, the driving gear being driven by the usual mechanism designed to produce both rotation and reciprocation thereof. The driving gear is furnished, in the usual fashion, with a cam groove 9 into which extends a follower roller carried by one arm of a bell crank 13 which serves, by its oscillation and suitable ratchet connections, to advance a pattern chain. In the present machine this arm carries other devices associated with the shogging mechanism.

The shaft 10 carries at its upper end a gear 12 driving a pinion 14 carried by a shaft journalled in a bracket of the frame. The shaft carrying the pinion 14 is provided with a lower member of a universal joint 16, the upper member of which is connected with one section of a two-part splined shaft 18 which, at its upper end, is connected through a universal joint 20, similar to 16, with a shaft 22 which carries a pinion 24 meshing with a ring gear 26. The universal joints are of the conventional type which will maintain the pinions 14 and 24 in a definite angular relationship irrespective of movements of translation of the pinion 24 so long as its axis remains parallel with the axis of the pinion 14. It will be noted that the universal joints, together with the splined arrangement, permit the axes to remain parallel in spite of the movements of the axis of the gear 24 about the axis of rotation of the needle cylinder, as will be hereafter described. The ring gear 26 is carried by the bobbin plate 28, which carries a bearing ring rotating on the top of the bracket 32 which, when in operative position, forms an integral part of the machine frame although it may be tilted about the axis indicated at 30 when the latch ring 31 is raised, or independently of said latch ring, the shaft 18, by reason of its splined construction, permitting this to occur. Secured to the bobbin plate is a tubular member 34 extending inside an opening in the bracket 32, which provides a bearing for it. The lower end of this member 34 carries the wrap finger supporting head 36, which is slotted and formed to provide a pivotal support for wrap fingers 38 held therein in the usual fashion by a spring band. These wrap fingers are actuated, as will be pointed out hereafter, by means of suitable character to cause the lower ends to move outwardly and inwardly between the needles 4 of the needle circle to produce wrapping, patterning being attained by the selection of needles. The lower ends of the wrap fingers are twisted in conventional fashion so as to be cammed by the needles to one side in passing outwardly and to the opposite side in passing inwardly. There is thereby produced a motion of the wrap finger about the needle which it is wrapping.

The bracket 32 is provided with an external bearing surface concentric with the axis of the wrap finger head and the needle cylinder in which is journalled a carrier 42. A lateral extension of the carrier 42 provides a journal for the shaft 22 and the pinion 24. By reason of the concentric mounting of the carrier 42 and the gear 26, it will be seen that the pinion 24 will remain in mesh with said gear irrespective of the position of the carrier. At the side of the machine illustrated in Fig. 1, the carrier is provided with an extension to which are secured ratchet plates 46, 48 and 50, illustrated in elevation in Fig. 9 and in plan in Figs. 10, 11 and 12. From the latter it will be seen that the teeth 66 and 90 of the plates 46 and 50 are directed in one direction while the teeth 84 of the plate 48 are directed oppositely. The carrier 42 is urged clockwise, as viewed in plan, by a weight 45 connected to the carrier through a spring 44 by a cable 43 passing over a pulley carried by a suitable fixed bracket.

An extension of the bracket 32 carries a stud 52 on which are journalled three levers 54, 56 and 58, these levers being provided with extensions carrying stop screws 59 urged into contact with an extension of the frame by individual springs 61 which urge the levers 54, 56 and 58 counterclockwise in opposition to actuating mechanism. At its upper end the first of these levers carries a stud 60 on which is journalled a pawl 62 the nose of which is urged towards the teeth 66 of the ratchet plate 46 by means of a spring 64 connected between the pawl and a post carried by the lever 54. A pin 68 carried by the pawl is arranged to engage the cam 70 carried by a fixed bracket 72 so that the pawl is held out of contact with the teeth when in its retracted position to which it is urged by its spring 61. As the lever 54 is moved clockwise as viewed in Fig. 9, the pawl 62 will move to the right, as shown in Fig. 10, so that it will engage a tooth 66 of the ratchet 46 as the pin 68 rides off the cam 70. The cam 70 is provided primarily to normally hold the pawl 62 away from the teeth to permit reverse movements of the carrier 42.

A rod 74 carried by the lever 54 is provided with a spear head 75 adapted to engage a cam 76 carried by the detent 78, which is mounted on a fixed stud 80 carried by the bracket 32 and urged by a spring 82 to bring its nose into engagement with teeth 84 of the ratchet plate 48. A lateral extension of the arm 54 pivotally supports a lever 77 which is urged by a strong spring 81 into engagement with a stop pin 79 carried by the extension. The lever 77 is in horizontal alignment with the sloping left-hand surface of the pawl 78, as viewed in Fig. 11. The arrangement of the parts is such that as rod 74 advances during forward movements of the pawl 62, the spear head 75 engages the cam 76 to disengage the detent 78 from a tooth 84 just prior to the engagement of the pawl 62 with a tooth 66. As the spear head moves further, its point passes beyond the inward point of the cam 76 thereby releasing the detent 78, permitting it to again move between the teeth 84 as soon as the pawl 62 has advanced the carrier 42 to such extent as to move the last engaged tooth 84 beyond the nose of the pawl 78. To insure that the pawl 78 moves inwardly, the lever 77 is urged to engage it to provide a force in addition to that exerted by the spring 82. The pawl is accordingly in position to engage the next tooth 84 before the pawl 62 reaches its ex-

treme forward position. The timing of these parts will be described in more detail hereafter. et designated 154. The two tricks wheels are simultaneously stepped about by the oscillations of a bell crank 156 which carries a pawl 158 engaging the teeth of the ratchet 136 under the action of a spring 160 and also a pawl 162 engaging the teeth of ratchet 154 under the action of spring 164. The bell crank 156 is oscillated during the operation of the machine by a link connection 166 to a lever 168 which is provided with a follower end adapted to be acted upon by lugs 170 of a pattern chain which is advanced in the usual fashion by the action of a pawl on the end of the oscillating arm 13. The ratchet 136 is provided with one low tooth 172 while the ratchet 154 is provided with a similar low tooth 174. A guard cam 176 pivoted concentrically with the trick wheel 135 is provided with three steps 178, 180 and 182 which are selectively engageable with the end of pawl 158 in its normal range of movement. A similar guard plate 183 is associated with the ratchet 154, being provided similarly with steps 184, 186 and 188 cooperating with the pawl 162. The two guard plates 176 and 183 are connected by a link 190. Guard plate 183 is provided with an extension 192 engageable by the lever 194 secured to a shaft 198 which is controlled by a suitable series of cams 196 carried by the cam drum, which is formed as an extension of the main pattern cam disc 151. When the steps 178 and 184 are opposite the paths of movement of the pawls 158 and 162, respectively, these pawls may engage all of the teeth of the ratchet plates, including the low teeth, and hence intermittently advance the trick wheels. This is the normal position of both of the guard plates during operation. If the high steps 182 and 188 engage the pawls, then the pawls reciprocate idly without engaging any of the teeth and consequently the trick wheels are stopped. This is the condition when it is desired that a temporary stopping of the trick wheels should be effected as, for example, during the reciprocatory knitting of the heel, when it is not desired to interrupt the continuity of the wrap pattern, which may extend from the ankle into the instep.

Mid-position of the guard plates brings the intermediate steps 180 and 186 adjacent the paths of reciprocation of the pawls. Under these conditions, the pawls will engage all of the normal teeth of the ratchets and will hence advance the trick wheels. They will, however, be positioned outwardly to such extent as not to engage the low teeth 172 and 174. Consequently, when these teeth come around, the pawls will reciprocate idly in engagement with the steps 180 and 186 and the trick wheels will remain at rest. The positions thus attained by the trick wheels are those desired at the beginning of the operation in the knitting of a new stocking. The patterns accordingly begin from positions corresponding to this location of the low teeth.

A number of devices are controlled from the main pattern drum through connections involving a plurality of concentrically nested shafts. Three of such shafts, as indicated in Figs. 4 and 8, are provided with arms 200 connected by means of individual links 202 to pivoted levers 204, which are provided with engaging elements 206 arranged to contact with the tails of levers 208, whose active ends 209 are located in position to engage butts on the lower jacks 7 as indicated in Figs. 6 and 14. The levers 208 are stacked, there being a plurality of them at a series of heights to cooperate with the butts on the lower

jacks. These levers are normally urged towards operative position by suitable individual springs, and under the action of such springs have follower portions thereof brought into position to be engaged by tricks on the trick wheel 152. The trick wheel is set up by the provision of a suitable butt arrangement to selectively actuate the various levers 208 and thereby cause the ends 209 thereof to selectively contact with the butts on the lower jacks. There are three levers 204 each of which acts upon a group of levers 208. When the levers 204 are rocked in a counter-clockwise direction as viewed in Fig. 2, their respective groups of levers 208 are rendered inoperative, being withdrawn both from the face 15 of the trick wheel and also from the paths of the butts of the lower jacks. At this point, there may be mentioned the fact that there is provided one lever of the same type as 208 located at the bottom of the stack, the active end of which is designated 211 in Fig. 14. This particular lever is not used for the same purpose as the others, but, as will be pointed out later, for the purpose of preventing the sole needles from rising to take wrap yarns during the knitting of 25 the foot. This particular lever is controlled from the main pattern drum through one of the nested levers by the connections indicated at 213.

Each of the links 202 is provided with a plurality of nuts forming an abutment for actuating a lever 212, which has an active end acting upon the extensions 214 provided on its corresponding set of levers 130. When any of the levers 204 is rocked to render the corresponding set of levers 208 inoperative, the corresponding triple set of levers 130 is, at the same time, rendered inactive by having the trick wheel follower portions thereof withdrawn from the trick wheel 135, as will be brought out in greater detail hereafter. The two trick wheels are correspondingly set up with the upper set of levers 208 corresponding to the upper set of levers 130 and so on. By such correspondence, not only is the setup of the design greatly facilitated, but very elaborate combinations may be attained.

Another of the nested shafts forming the group just referred to carries an arm 216 which is link-connected to a composite adjustable arm 218 carrying a cam 220. The location of this cam relative to the active ends 209 of the levers 208 is indicated in Fig. 14.

Referring more particularly to Fig. 14, wherein is illustrated the relationship of the various cams acting upon needles, jacks and wrap fingers, the usual knitting cams are provided including, 55 among others, the upper center cam 222 and the stitch cams 224 and 226, the latter of which serves to draw down the needles during rotation. These are associated with the usual pickers, switch cams, etc., and in the embodiment shown, 60 also with gusset cams which, however, form no part of the present invention. Located in the relative positions indicated are various jack cams including a jack-raising cam 228 which is adapted to engage shoulders 231 provided on the 65 jacks to raise the jacks and, through them, the needles, to a position where the needles may take wrap yarns. Wrapping occurs when the shoulders 231 of the jacks rest upon the surface 230 of the cam 228. Thereafter the inwardly bevelled surface 232 of the cam serves to disengage the shoulders 231 from the cam 228. The cam surface 223 then engages the butts on the intermediate jacks to draw the intermediate and lower jacks downwardly. A guard cam 234 prevents 75

downward overrun of the lower jacks. A cam 236 provided with a leveling surface 238 serves to raise the lower jacks accurately to position where their various butts will be properly aligned with the 5 active ends 209 of the jack pressing levers. As indicated in Fig. 6, the jacks are formed so that they may rock within the needle slots. A cam 220 serves to insure the outward movement of the lower ends of the jacks to bring the shoulders 237 10 into position for engagement with the cam 236.

The principal selection for wrapping occurs due to the selective raising of needles as just indicated. Some selection of wrap fingers, however, is made, and adequate means must be provided for causing the wrap fingers to move outwardly through the needle circle and then inwardly to cause them to place yarn within the hooks of the needles to be wrapped. Cams 240 and 242 engage upper and lower butts of the 15 wrap fingers respectively. A cam 244 arranged to engage the wrap fingers below their pivots tends to return their lower ends within the needle circle. The cams 240 and 242 are pivoted upon a vertical pin and are selectively rendered operative by being moved inwardly through the action of cam levers 246 against the tension of their respective springs 241 and 243. The levers 246 are engaged by the upper ends of levers 248, which are rocked by the action of arms 250 carried by 20 shafts nested upon the shaft 198. These shafts are provided with arms 252 engageable by cams on the main pattern drum.

The operations involved in producing shogging may now be described. The specific set up of the 35 trick wheels will be later referred to. However, for the present, it may be pointed out that in the absence of a butt on a trick engaging the follower end of a lever 130, such lever will be urged to its extreme counterclockwise position, 40 as viewed in plan, by its spring 136, and will then engage the corresponding pin 132 to rock the lever 118 clockwise against the tension of its spring 122. The springs 122 as well as the springs 112 are weaker in their effects than the springs 136. As the arm 13 swings rearwardly, 45 the lever 108, which lies in the path of the pin 117 of the clockwise positioned lever 118, will engage such pin, with the result that the horizontal portion of that lever 108 will be positioned below the plane of the guard 110. The 50 setup of the trick wheel will be such that at this same time the other two levers 118 will be in their proper counterclockwise positions, since the corresponding levers 130 will be engaged by butts on the trick wheel while the other groups of levers 130 will be held away from tricks by their levers 212. In the rearward stroke, when 55 the engaged lever 108 strikes the stop pin 116, the corresponding lever 118 and its actuating lever 130 will yield against the corresponding spring 136 to some slight extent. Upon the subsequent forward oscillation of the lever 13, the lever 108, which has been engaged, will pass under the guard 110 while the other levers will extend above 60 this guard. By reason of its backing by the guard 110, the lever 108 will engage the pin 106 of the corresponding lever 100 and will rock the same counterclockwise, as viewed in Fig. 1, against the action of its spring 102. From this it will be 65 obvious that with a proper setup of butts in the trick wheel, the three levers 100 may be selectively rocked; this in turn serves to rock clockwise the respective levers 54, 56 and 58 with the results 70 which will now be described.

75 The operation of forwardly shogging the wrap

fingers relatively to the needles is effected by a stroke of the lever 54. The stroke imparted to the corresponding lever 100 is such that if there were no interruption of the forward movement of the pawl 62 the pawl would advance to carry the plate 46 through an angular distance greater than the angular spacing between adjacent teeth 66. As will be pointed out, such movement is prevented, the excess movement imparted to the corresponding lever 100 being taken up in a slight 10 springing of the levers 100 and 54. As the lever 54 begins its forward movement and before the pawl 62 engages a tooth 66, the detent 78 is released from the tooth 84, in front of which it lies, by the action of the spear head 75 upon the cam 76. 15 In general, the detent 78 would not engage a tooth at this time but would have a very slight clearance therewith, the carrier being positioned by engagement of one of the detents 86 or 88 with a tooth 90 under the action of the weight 20 45. As soon as the detent 78 is moved out of the path of the tooth 84, the pawl 62 engages a tooth 66 and advances the carrier against the action of the weight 45. As soon as the tooth 84 previously lying against the detent 78 moves 25 therebeyond, the detent 78 is released and positively forced into the path of the next tooth 84 by the action of the spring 82 and the spring-tensioned lever 71. Thereafter the pawl 62 continues to advance the carrier, this advance stopping when the next tooth 84 engages the pawl 78. The excess movement imparted to the lever 100 is then taken up by springing of the parts. By 30 providing for this, there is definite assurance that a tooth 84 will be engaged with the detent 35 78. As engagement of a tooth 84 with the detent 78 takes place, one of the detents 88 or 86 will drop in front of the next tooth 90 so that, when the pawl 62 is withdrawn, one of these 40 detents will hold the carrier in its advanced position. In view of the action of snubbing pawl or detent 78 which substantially tends to hold the carrier in the same position as the detents 86 and 88, the wrap fingers are positioned relatively to the needles for wrapping even before 45 the forward effort applied to the pawl 62 has ceased and, of course, considerably before it is permitted to move in its retracting stroke. The period of advance of the carrier is thus cut down to such extent that wrapping is interrupted for 50 only a relatively short time which in practice is found to be of the same order as the time during which wrapping must be interrupted to permit reverse movements of the carrier, since, of course, 55 wrapping cannot take place during the relative movements of the wrap fingers and needles inasmuch as the wrap fingers pass through the needle circle.

Reversing of the carrier takes place by the alternate tripping of the detents 86 and 88 and 60 the effort of the weight 45. Such tripping is, of course, effected by movements of the corresponding levers 100. The pawl or detent 78 will yield to permit the teeth 84 to pass during such reverse shogging movements, while the pawl 62 is 65 held out of the path of teeth 66 by the cam 70. The use of the weight 45 insures an even tension being exerted upon the detents and pawl 62 in all positions of movement of the carrier. A short spring is somewhat unsatisfactory for this 70 purpose, since the tension changes very substantially as the shogging takes place from the central position. The spring 44 interposed in the cable 43 serves to smooth out the intermittent movements of the weight 45, which then, by 75

reason of its inertia, relatively slowly follows the movements of the carrier. Swinging and jarring movements are thus minimized.

- If, instead of alternatively tripping the detents 5 86 and 88, both of them are tripped simultaneously, the carrier 42 will move to an extreme position determined by engagement of the adjustable stop 97 with the portion of the frame indicated at 99. By reason of this arrangement, it is 10 possible to produce forward shogging in individual needle steps and then instantaneously cause a return of the carrier to its extreme clockwise position. Interrupted shogged patterns may be 15 thus produced or, alternatively, shogged patterns of considerable complication. The adjustable stop 97 is preferably carried by a removable arm so that, under usual circumstances, the full range 20 of the ratchets may be used to produce wide shogged patterns.
- 20 The above describes the general operations involved in forward and backward shogging of the wrap fingers relative to the needles. The advance of the wrap finger carrier through the medium of movement of the pinion 24, which forms 25 an element of the epicyclic gear train providing the drive between the needle cylinder and the wrap finger carrier, may be noted. The operation will be clear from a consideration of what would occur if the needle cylinder and gears 12 and 14 30 were held stationary and movements were imparted to the carrier 42. In such case the angular position with respect to the frame of the machine of the pinion 24 would remain fixed, inasmuch as universal joints are of such type that the 35 angular relationship between pinions 24 and 14 when the wrap finger head is in its operative position is fixed, since then the axes of the two pinions always remain parallel. Under such conditions, it is obvious that a movement of the carrier 42 will cause a rotation of the gear 26 and consequently of the wrap fingers associated therewith, serving to displace the wrap fingers so as to carry them into cooperative relationship with 40 different needles. The teeth 46 are angularly spaced so that the angle between any pair of them corresponds to the angular movement of the carrier 36 equal to the angular spacing of adjacent needles. As a result, successive advances of the carrier 42 through angles corresponding to the 45 spacings of the teeth 46 will result in successive positions of the wrap fingers in operative relationship to successive needles. While the above is discussed from the standpoint of having the needle cylinder and driving connections stationary, it will be obvious that the same results will 50 occur when the needle cylinder is moving if the carrier is stepped about in the same fashion, so that the total movement of wrap fingers in any given time is equal to the algebraic sum of the 55 rotary movement of the needle cylinder and the movement due to the stepping of the carrier 42. Accordingly, by the operation of the pawls as described above, the wrap fingers are caused to operate with successive needles in successive 60 courses during rotary knitting. It may be pointed out that the angular spacing of teeth 46 is not equal to the angular spacing of the needles, the spacing being different to an extent depending upon the ratio of the pinion 24 to the gear 26.
- 65 70 As has been pointed out above, selective wrapping is effected by raising needles into position to receive the wrap yarns, those needles which are not raised being unwrapped, even though the wrap fingers may pass through their usual wrapping movements, as will in general be the

case. The operation of selecting needles may be best described with reference to Figs. 6 and 14. Following the drawing of the stitches, the needles and jacks will be in lowered positions. As lower jacks pass the location of the cam 220, 5 their upper ends will be engaged thereby with the result that their lower ends will be rocked outwardly, bringing their shoulders 237 into position to engage the cam 238. This cam serves to level the jacks to a proper position so that their butts at various levels will be aligned properly with corresponding active ends 209 of the levers 208. By providing the lower jacks with butts properly arranged, and by providing butts in proper locations on the tricks of the 10 trick wheel 152, certain of the lower jacks will be rocked inwardly by engagement of levers 208 with their butts. The jacks whose lower ends are thus rocked inwardly will fail to engage the cam 228 and consequently will remain at their 15 low level and will not force upwardly their corresponding needles to take wrap yarn. Such needles will then remain unwrapped.

20 On the other hand, those jacks whose lower ends were not rocked inwardly will have their 25 shoulders 237 engaged by the rising surface of the cam 228 and will rise to positions corresponding to the level 230, when their needles will have been raised to position to take wrap yarns presented by the wrap fingers, which are then rocked 30 outwardly and later inwardly by the action of cams 240, 242 and 244. Following this, the intermediate and lower jacks are forced downwardly by the action of cam 223, leaving the needles free 35 to pass through the usual knitting wave over cam 224 and beneath cams 222 and 226.

The operation of the machine in the knitting of a stocking will now be described, particular 40 reference being made to Figs. 15A and 15B, the latter of which is a continuation of the former, 45 which figures illustrate a simple pattern producible by the use of the mechanism already described. The two figures overlap to some slight extent, the identical courses being indicated at X. The diagram illustrates a clock formed in a stocking 50 whose courses and wales are represented by the rows and columns of squares respectively. The hatched squares at the left of the diagram represent the loops which are wrapped, while at the right of the diagram there is indicated, by 55 the zigzag line, the progress of shogging throughout the making of the pattern. The initial setup of the wrap fingers in relation to the needles with which they cooperate is indicated at W. The pattern, down to approximately the 60 point A, is governed by the setup of the trick wheel operating upon the lowermost set of levers 130 and also the lowermost set of levers 208. The portion from A to B is controlled by the trick wheel setup acting on the intermediate set of 65 levers 130 and the intermediate set of levers 208. The portion from B to C is controlled by the uppermost corresponding sets of these levers. In the operation, the portion down to the point A may be formed by substantially a complete revolution of each trick wheel. It will be noted that the initial short shog at the top of the clock would again appear if the trick wheel made more than a single revolution while the lower set of levers 130 and 208 were active. To avoid this, 70 the lower sets of levers are rendered inactive through the medium of the lever 209 and the connections thereto and the intermediate sets of levers are put into operation. As pointed out, these may form the portion A to B. In some 75

instances it might be desirable that the intermediate portion of a design should be repeated in whole or in part. Under such circumstances, the trick wheel could make more than a revolution up to, for example, a plurality of revolutions, either complete or partial. The upper set of levers can then be rendered active in place of the intermediate set to finish the pattern, as indicated, between B and C. Some of the pattern may be discontinued as indicated at H, where the clock stops at the top of the heel.

If H represents the point of beginning the heel, this will be the time when the high steps of the guard plates 176 and 183 are brought into engagement with the pawls so that the pawls may reciprocate idly during the reciprocal knitting of the heel while the trick wheels retain their positions to continue operation during the formation of the foot portion of the stocking.

Following the completion of the desired design, all of the levers 130 and 208 may be rendered inactive. The levers 128 are then rendered active by control of the lever 144 by the main cam disc with the result that shogging takes place as indicated at D, serving to bring the wrap finger carrier into its initial position relative to the needles. After this has been accomplished, for example, during the formation of the ring toe, all of the trick wheel followers, namely the levers 130, 128 and 208, as well as 211, may be rendered inactive while stepping of the trick wheels continues with the intermediate steps 180 and 186 opposite the respective pawls 158 and 162. The trick wheels will then be stepped around until the low teeth 172 and 174 come opposite the pawls, whereupon the trick wheels will stop in their initial positions ready for control of wrapping of a subsequent stocking.

It is desirable to provide the levers 128 and the upper tricks of wheel 135 for emergencies, although this may not be necessary, since the return to initial shogging may be effected during the latter part of the rotation of the trick wheel 135 if such latter rotation is not necessary for the production of shogged patterns. During the restoration of the wrap fingers to initial position, wrapping may be discontinued either by a proper setup of the needle selecting trick wheel 152 or by the control of cams 240 and 242. The discontinuation of the portion of the wrap design which might extend into the heel or the lower portion of the foot can also be effected by a proper setup of wrap fingers, those wrap fingers, for example which cooperate with needles located at the rear of the stocking being provided with upper butts, whereas the front needles are provided with lower butts. If, therefore, the cam 240 is rendered inactive while 242 remains active, there will be no wrapping occurring on the rear needles. The beginning or cessation of wrapping may, of course, be effected in numerous ways, as indicated in the description, by the use of the various controls. Needle selection, for example, by the use of the auxiliary lever 211 may be provided to cut out wrapping on any desired set of needles associated with jacks having butts in position to be engaged by the lever 211.

One desirable mode of operation is indicated in the diagram, in which, at first glance, it might appear that unnecessary shogging takes place. This is indicated in the upper portion of Fig. 15A, although the same type of operation occurs in other portions of the same design. By a substantial amount of shogging during the produc-

tion of a straight portion, the floats F may be tied into wrapped loops, as indicated, so as to minimize the lengths of vertical floats and avoid the necessity for cutting them out.

What I claim and desire to protect by Letters Patent is:

1. A knitting machine including needles, fingers arranged to feed wrap yarns to the needles, means for shogging the fingers relatively to the needles, and pattern mechanism for controlling the shogging means, said pattern mechanism including a plurality of pattern controlling devices, separate sets of followers actuated by said devices and arranged to effect shogging movements, each set including independent followers for producing both forward and backward shogging, and means for rendering said sets of followers selectively operative whereby the shogging is selectively controlled by the various devices to produce different patterns.

2. A knitting machine including needles, fingers arranged to feed wrap yarn to the needles, means for shogging the fingers relatively to the needles, said shogging means comprising ratchet mechanism, an oscillating member, a plurality of elements carried by said oscillating member, a corresponding plurality of abutments, each selectively movable to operative or inoperative position and arranged, when in operative position, to engage and set up a corresponding element in movement in one direction to arrange it to control said ratchet mechanism during movement in the opposite direction, sets of pattern mechanism moving together cyclically side by side and adapted to dictate different shogging sequences, devices joining each of said abutments with each of said sets of pattern mechanism, and means for rendering the sets selectively active, whereby the shogging sequences during successive cycles of said sets may be varied.

3. A knitting machine including needles, fingers arranged to feed wrap yarns to the needles, means for shogging the fingers relatively to the needles, said shogging means comprising ratchet mechanism, a plurality of members, each selectively movable to operative or inoperative position and arranged, when in operative position, to effect predetermined control of the ratchet mechanism, sets of pattern mechanism moving together cyclically side by side and adapted to dictate different shogging sequences, devices joining each of said members with each of said sets of pattern mechanism, and means for rendering the sets selectively active, whereby the shogging sequences during successive cycles of said sets may be varied.

4. A knitting machine including needles, fingers arranged to feed wrap yarns to the needles, means for shogging the fingers relatively to the needles, said shogging means comprising ratchet mechanism, sets of pattern mechanism moving together cyclically side by side and adapted to dictate different shogging sequences, devices associated with said sets of pattern mechanism and adapted to control the ratchet mechanism, there being associated with each set of pattern mechanism a plurality of such devices having different functions, each of which functions is represented by one such device associated with each set of pattern mechanism, and means for rendering the sets selectively active, whereby the shogging sequences during successive cycles of said sets may be varied.

5. A knitting machine including needles, fingers arranged to feed wrap yarns to the needles,

- means for shogging the fingers relatively to the needles, sets of pattern mechanism moving together cyclically side by side and adapted to dictate different shogging sequences, each of said sets of pattern mechanism being provided with separate series of elements for controlling forward and backward shogging movements, separate members operative to effect forward and backward shogging movements, means whereby each of said members is operable by elements of corresponding function in all of said sets, and means for rendering the sets selectively active, whereby the shogging sequences during successive cycles of said sets may be varied.
5. A knitting machine including needles, fingers arranged to feed wrap yarns to the needles, means for shogging the fingers relatively to the needles, sets of pattern mechanism moving together cyclically side by side and adapted to control the shogging means to dictate different shogging sequences, means for moving said sets through only a small portion of a cycle during the knitting of any course, means for rendering the sets selectively active during wrapping to 10 control the shogging means whereby the shogging sequences during successive cycles of said sets may be varied, and means for rendering one of the sets active during a period of knitting when no wrapping is taking place to restore the fingers to an initial position relative to the needles.
15. 6. A knitting machine including needles, fingers arranged to feed wrap yarns to the needles, means for shogging the fingers relatively to the needles, a plurality of members, each selectively 20 movable to operative or inoperative position and arranged, when in operative position, to effect predetermined control of the shogging means, sets of pattern mechanism moving together cyclically side by side and adapted to dictate different shogging sequences, devices joining each of said
7. A knitting machine including needles, fingers arranged to feed wrap yarns to the needles, means for shogging the fingers relatively to the needles, a plurality of members, each selectively 25 movable to operative or inoperative position and arranged, when in operative position, to effect predetermined control of the shogging means, sets of pattern mechanism moving together cyclically side by side and adapted to dictate different shogging sequences, devices joining each of said

members with each of said sets of pattern mechanism, and means for rendering the sets selectively active, whereby the shogging sequences during successive cycles of said sets may be varied.

8. A knitting machine including needles, fingers arranged to feed wrap yarns to the needles, means for shogging the fingers relatively to the needles, sets of pattern mechanism moving together cyclically side by side and adapted to dictate different shogging sequences, devices associated with said sets of pattern mechanism and adapted to control the shogging means, there being associated with each set of pattern mechanism a plurality of such devices having different functions, each of which functions is represented by one such device associated with each set of pattern mechanism, and means for rendering the sets selectively active, whereby the shogging sequences during successive cycles of said sets may be varied.

9. A knitting machine including needles, fingers arranged to feed wrap yarns to the needles, means for shogging the fingers relatively to the needles, sets of pattern mechanism moving together cyclically side by side and adapted to dictate different shogging sequences, each of said sets of pattern mechanism being provided with separate series of elements for controlling forward and backward shogging movements, followers, one of which is associated with each of said series of elements, separate members operative to effect forward and backward shogging movements, each of said members being controlled by a plurality of followers, one belonging to each 30 of said sets, and means for rendering the sets selectively active, whereby the shogging sequences during successive cycles of said sets may be varied.

HAROLD E. HOUSEMAN. [L.S.]
